UNITED STATES PATENT OFFICE.

ELEAZAR MYERS, OF LEONIA, NEW JERSEY, ASSIGNOR TO THE COLUMBIA MILLS,
INCORPORATED, A CORPORATION OF NEW YORK.

FABRIC CLAMP.

Application filed April 15, 1924. Serial No. 706,659.

To all whom it may concern:

Be it known that I, ELEAZAR MYERS, a citizen of the United States, residing at Leonia, in the county of Bergen and State 5 of New Jersey, have invented certain new and useful Improvements in Fabric Clamps, of which the following is a specification.

This invention is a clamping device primarily intended for clamping fabrics, such 10 as fabrics out of which curtains are made, while size, varnish, paint or other coating material is applied thereto. The clamping device, however, is of course, adapted for other uses.

15 The clamp comprises essentially a channeled member, an elongated clamping strip and a manually operated device for forcing the clamping strip to a position to clamp the fabric in the channeled member.

20 One of the important features of the invention is the fact that the elongated clamping strip is quite separate from and not secured to the cam or other eccentric means that is used to force the strip to clamping 25 position.

This freedom of the clamping strip from the eccentric presents several advantages: the clamping strip may be very readily removed and soaked in a cleansing solution.

30 Remembering that the strip is liable to be spattered with paint, varnish or size, this is a valuable feature.

Again, if one of these clamping strips is bent, or becomes rusted or otherwise unsuitable for use, it can be immediately replaced 35 without the necessity of dismounting the same.

Still another advantage of this free clamping strip is that it may be reversed or 40 turned over, a feature which is particularly valuable in connection with a strip which may be made thinner along one longitudinal edge than along the other. With such a clamping strip of variable thickness, a variable clamping action between the clamping strip and the channel member is obtained, 45 which is particularly useful for clamping fabrics of different thickness.

Referring now to the drawings in which 50 a preferred embodiment of the invention is shown:

Fig. 1 is a side elevation of the clamping device;

55 Fig. 2 is a section on the line 2—2 of Fig. 1;

Fig. 3 is a view similar to Fig. 2 showing the parts just before they are in clamping position;

Fig. 4 is a side view of the eccentric or cam showing a slight modification, and 60

Figs. 5 and 6 show two modifications of the clamping strip.

Referring now to these drawings, on the base 1, preferably of wood, is mounted the channeled member 2, being secured to the 65 base in any suitable manner. Channeled member 2 is preferably made of metal, such as sheet iron.

The clamping strip 3 is an elongated piece or strip of narrow, flat material, preferably 70 iron. It is forced to clamping position by a cam or eccentric 4 pivoted on the bolt 5 and provided with an operating handle 6. The lower edge of the eccentric is of varying 75 radius and is provided with a stepped portion 7 backed by a flange 8 which stepped portion bears against the top edge of the clamping strip to force it downwardly and laterally to clamping position. The eccentric bears against the strip 3 to a point substantially directly below the pivot 5, so that 80 there is no tendency of the eccentric to become released after it is in clamping position.

As indicated in Figs. 2 and 3, the fabric 85 F is clamped in the channeled member 2 by the strip 3.

In the modification shown in Fig. 4, the lower edge of the eccentric may be grooved as indicated at 10, the side walls of the 90 groove straddling the upper edge of the clamping strip 3.

Fig. 5 shows a modification of the clamping strip 3 where one longitudinal edge 3' is thinner than the other longitudinal edge 95 3'', for giving a variable clamping action. The thinner or thicker edge is chosen for the lower edge of the clamping strip, according as thick or thin fabric is being clamped.

Fig. 6 shows another modification of the clamping strip 3 wherein an arcuate depression 3^a is provided in one edge of the clamping strip, in which depression the edge of the eccentric 4 is adapted to seat.

In addition to the reversibility of the clamping strips, their ease of cleansing and replacement, and their variable thickness for clamping thin or thick material, another very important advantage is obtained by 110

this invention, namely a decreased cost of replacement of the clamping strips due to their simple design.

These clamps are used in great quantities in coating fabric material, being used not only for holding the strips of fabric at their upper ends, but also to clamp the fabric along the bottom edges to weight it down and keep it smooth and taut. Since the 10 coated fabric takes some time to dry, and it has to remain in the clamps until dry, it means that these clamps must be used in great numbers, and therefore, it is very important from a commercial point of view to 15 keep the cost of such clamps at a minimum. For example, to illustrate how many of these clamps are required, it may be stated that it takes forty-five hundred clamps, each two feet long, to handle the cloth necessary for 20 a gang of three men.

This clamp can be used for clamping any strip or sheet material and is not limited to fabric. The term "fabric" as used in the 25 claims is used in an illustrative and not a limiting sense.

While a preferred embodiment of the invention, and certain modifications, have been illustrated, it should be understood that the invention is not limited to the exact construction shown, but may be carried out in other ways, as falling within the scope of the 30 appended claims.

I claim as my invention:

1. In a device of the character described, 35 the combination of a base, a channeled member mounted thereon, a clamping strip for clamping fabric in the channeled member, and eccentric means movable about an axis substantially perpendicular to the base and 40 unattached to the clamping strip for forcing it to clamping position, the clamping strip being freely removable.

2. In a device of the character described, 45 the combination of a base, a channeled member mounted thereon, an elongated clamping strip which varies in thickness from one longitudinal edge to the other for clamping fabric in the channeled member, and eccentric means pivoted on an axis substantially 50 perpendicular to the base, for forcing the clamping strip to clamping position.

3. In a device of the character described, 55 the combination of a base, a channeled member mounted thereon, an elongated and reversible clamping strip which varies in thickness from one longitudinal edge to the other for clamping fabric in the channeled

member, and means for forcing the clamping strip to clamping position.

4. In a device of the character described, 60 the combination of a base, a channeled member mounted thereon, an elongated and reversible clamping strip which varies in thickness from one longitudinal edge to the other for clamping fabric in the channeled 65 member, and eccentric means pivoted on an axis perpendicular to the base for forcing the clamping strip to clamping position.

5. In a device of the character described, 70 the combination of a base, a channeled member mounted thereon, an elongated clamping strip for clamping fabric in the channeled member, and a grooved eccentric pivoted on an axis substantially perpendicular to the base for straddling an edge of the clamping 75 strip and forcing it to clamping position.

6. In a device of the character described, 80 the combination of a base, a channeled member mounted thereon, an elongated and reversible clamping strip for clamping fabric in the channeled member, and a grooved eccentric for straddling an edge of the clamping strip and forcing it to clamping position.

7. In a device of the character described, 85 the combination of a base, a channeled member mounted thereon, an elongated and reversible clamping strip which varies in thickness from one longitudinal edge to the other for clamping fabric in the channeled member, and a grooved eccentric for straddling an edge of the clamping strip and forcing it to clamping position.

8. In a device of the character described, 90 the combination of a base, a straight elongated J-shaped channeled member mounted thereon, with its wide side against the base, a straight elongated clamping strip for clamping a strip of material in the channeled member, and eccentric means, pivoted on an axis perpendicular to the base, and unattached to the clamping strip, for forcing it to clamping position.

9. In a device of the character described, 95 the combination of a flat base member, a long, straight trough-like channeled member secured to the base, a long substantially flat clamping strip adapted to fit into the trough of the channeled member and clamp a fabric therein, and eccentric means pivoted on the base on an axis perpendicular thereto for forcing the clamping strip to clamping position.

In testimony whereof I affix my signature.
ELEAZAR MYERS.
